(57) **CLAIM**

The ornamental design for a bottom weight for a blind, as shown and described.

DESCRIPTION

FIG. 1 is a perspective view of a bottom weight for a blind; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The bottom weight for a blind includes a break along its length showing the manner of assembly of the two parts of the design. The area between the break lines forms no part of the claimed design.
